(57) **CLAIM**

The ornamental design for an adapter for a mounting assembly for electronic devices, as shown and described.

DESCRIPTION

FIG. 1 is a front perspective view of the adapter for a mounting assembly for electronic devices according to the present design;

FIG. 2 is a front elevational view of the adapter for a mounting assembly for electronic devices of FIG. 1;

FIG. 3 is a rear elevational view of the adapter for a mounting assembly for electronic devices of FIG. 1;

FIG. 4 is a right-side elevational view of the adapter for a mounting assembly for electronic devices of FIG. 1;

FIG. 5 is a left-side elevational view of the adapter for a mounting assembly for electronic devices of FIG. 1;

FIG. 6 is a top plan view of the adapter for a mounting assembly for electronic devices of FIG. 1; and,

FIG. 7 is a bottom plan view of the adapter for a mounting assembly for electronic devices of FIG. 1.

The broken lines depict environmental structure that forms no part of the claimed design.

1 Claim, 7 Drawing Sheets
